United States Patent Office

Des. 204,052
Patented Mar. 15, 1966

204,052

URINAL

Al G. Hilde, Jr., 925C Kingsview Lane,
Minneapolis, Minn.

Filed Apr. 12, 1965, Ser. No. 84,715

Term of patent 14 years

(Cl. D4—5)

FIG. 1 is a front elevational view of a urinal embodying my novel design;

FIG. 2 is a rear elevational view thereof;

FIG. 3 is a cross-sectional view taken approximately along line 3—3 of FIG. 1 and looking in the direction of the arrows.

FIG. 4 is a side elevational view thereof.

FIG. 5 is a top plan view thereof;

FIG. 6 is a bottom plan view thereof; and

FIG. 7 is a cross-sectional view on an enlarged scale taken approximately along line 7—7 of FIG. 4 in looking at the arrows.

I claim:
The ornamental design for a urinal, as shown.
